HOT CATHODE ELECTRON DISCHARGE TUBE

Original application filed January 8, 1923, Serial No. 611,263. Divided and this application filed July 6, 1926. Serial No. 120,582.

The invention relates to hot cathode electron discharge tubes and it has particular relation to grid-controlled tubes in which the electron emitting cathode is so heated from a source of alternating or, in general, fluctuating current as to substantially eliminate the undesirable effects of the variations of the heating current upon the electron flow in the tube.

Various cathode structures adapted for that purpose have been disclosed in our co-pending application Serial No. 611,263, filed Jan. 8, 1923, of which the present application is a division.

Among the objects of the invention is an improved construction of an efficient cathode having the above-mentioned characteristics which may be readily manufactured and which gives a particularly high degree of elimination of the undesirable controlling effects of the alternating heating current on the electron flow in the tube.

In the preferred form of the invention, a flat ribbon of tungsten is doubled to form a U-shaped heating member having a pair of adjacently positioned side sections. A thin sheet of mica, or other suitable refractory insulating material, is placed between the two sides of the U-shaped strip and serves to insulate the same from each other. The cathode element proper is constituted by strips of nickel placed on both sides of the U-shaped tungsten strip and insulated therefrom by mica-sheet pieces, or in any other suitable manner. The outer surface of the nickel strips treated with oxides having high electron emissivity and the several strips so assembled are clamped together and form a unitary cathode structure.

Inasmuch as the thin spacer utilized in the foregoing construction to insulate the two sides of the heater element from each other, permits close spacing between the parallel portions of the heater element, the magnetic fields produced by the currents flowing in one side of the heater element will be substantially fully neutralized by the return current flowing in the other, thus giving a construction which is ideal from the viewpoint of

eliminating the undesirable magnetic control of the electron flow in the tube.

The invention will be best understood from the accompanying drawing, in which

Figure 1 is an enlarged sectional view of an electron discharge tube, combined with a diagrammatic view of the associated circuits, embodying the invention, and

Fig. 2 is an enlarged perspective view of the top portion of the cathode structure utilized in the tube shown in Fig. 1.

Referring to the drawing, a radio-receiving tube of a familiar type is shown comprising an elongated envelope 1 of glass or similar material, having a re-entrant stem 2 terminating in a press 3 in which are welded five lead-in wires 4 to 8, which serve to support, and to provide connections to, a cathode member 10, a grid 12 and a plate 13 arranged concentrically, in the usual way.

The cathode member 10, to which this invention particularly relates, comprises a heater element in the form of a U-shaped strip or ribbon 15 of tungsten or other suitable material. The ribbon is preferably of flat cross section and is doubled upon itself, the two sides 16 of the ribbon being insulated from each other to prevent short-circuits between the same. This may be done by inserting a thin strip or sheet 17 of mica, or other suitable insulating material capable of withstanding the temperatures at which the heating element operates, between the two flat sides of the U-shaped ribbon heater 15.

The cathode element proper is constituted by two flat sheets of conducting material 18, such as nickel, assembled on both sides of the ribbon heater 15, the outer cathode surface sheets being insulated from the adjacent ribbon sides 16 like the two sides 16 of the U-shaped ribbon element, for instance, by mica sheets 19 placed therebetween.

The outer surface of the cathode sheets 18 are, of course, treated to have high electron emission, for instance by coating the same with oxides of barium, strontium and the like.

The several sheet or strip members so assembled are suitably held together, for in-

stance, by collar members 21, which tightly embrace the several elements at the upper and lower ends, respectively, thus uniting the same into a compact structure.

5 The cathode member 10, so obtained, is supported at its upper end by means of a bail extension 22 secured to the upper collar 21 and welded, or otherwise secured to a carrier rod 23, which extends from lead-in 10 wire 4. The bail connection between the upper collar 21 and the carrier rod 23 may also serve as the electrical lead to the active surface 18 of the cathode element and, in such case, the lead-in connection 4 to the carrier rod 23 may serve as a terminal of the cathode element.

At its lower end, the cathode member is supported through the connections of the ends of the U-shaped heater ribbon 15 to the 20 lead-in wires 5 and 6 which serve to convey thereto the heating current. When utilizing an electron tube as described above, the cathode is heated from a source of alternating-current, such as a transformer 25, the 25 other connections to the tube being made in the usual way. Thus, for instance, the input leads 26 of the circuit may be connected between the grid and cathode terminals 7 and 5, respectively, while the output leads 27 30 may be connected between the plate terminal 8 and the cathode terminal 4, respectively.

A cathode structure of the type described above, wherein a flat heater ribbon is used 35 as a heating element, permits the construction of a very compact cathode, in which the magnetic fields induced by the alternating heating current are eliminated to a higher degree than is possible with the other available constructions. It is, of course, understood that many other constructions embodying 40 the ideas disclosed hereinabove will suggest themselves to those skilled in the art, and the appended claims are intended to cover all such constructions.

We claim as our invention:

1. In a hot-cathode electron discharge tube, a cathode member comprising a V-shaped flat ribbon heater element having adjacently disposed sides and a flat sheet element of conducting material disposed adjacent to the surface of said heater element and separated therefrom by a layer of insulating material.

50 2. In an electron discharge tube, a cathode member comprising an even member of conducting ribbon heater elements disposed with the flat sides adjacent to each other, conducting sheet elements adjacent the outer sides of said adjacently-disposed heater elements, the adjacent surfaces of said heater elements and outer sheet elements being insulated from each other, and the outer surfaces of said outer sheet elements being electron-emissive.

65 3. In an electron discharge tube, a cathode

member having a heater element comprising an even number of longitudinal sheet elements having the flat sides disposed adjacent to each other, electron-emitting cathode elements disposed adjacent the outer surfaces 70 of said sheet elements, the cathode elements being insulated from the adjacent surfaces of the heater element.

4. In an electron discharge tube having a heater element comprising an even number 75 of sheet elements disposed with the flat sides opposite each other, electron-emitting sheet elements disposed adjacent the outer surfaces of said first-mentioned sheet elements, the individual sheet elements being insulated 80 from each other by layers of refractory insulating material interposed between the adjacent surfaces thereof.

5. In an electron discharge tube, a cathode member comprising a U-shaped ribbon heater 85 element having adjacently disposed flat sides, conducting sheet elements disposed adjacent the outer surface of said heater element, and having electron emitting outer surface portions, and layers of insulating material 90 interposed between the adjacent surfaces of the several elements.

6. In an electron discharge tube, a U-shaped flat ribbon element having adjacently disposed flat sides adapted to be heated by 95 sending current therethrough, and electron-emitting surface means adjacent to the surface of said ribbon element and insulated therefrom, and means for providing individual terminal connections to said heater ribbon and said cathode element respectively.

7. In an electron discharge tube, a cathode structure having a heater element comprising a pair of serially-connected ribbon sections disposed with their flat sides facing each 105 other, and electron-emitting sheet elements having flat sides facing the outer surfaces of said ribbon sections, the several facing surfaces being electrically insulated, but having a relatively good heat-conducting connection.

8. In an electron discharge tube, a cathode structure comprising a pair of parallel-disposed, serially-connected heater ribbons having the flat sides facing each other, electron emitting conducting sheet elements disposed adjacent the outer sides of said ribbon elements, and insulating sheet elements interposed between the surfaces of said elements that face each other.

9. In an electron discharge tube, a cathode structure comprising a pair of parallel-disposed serially-connected heater ribbons having their flat sides facing each other, electron-emitting conducting sheet elements disposed adjacent the outer sides of said ribbon elements, the adjacent facing surfaces being separated from each other by sheets of mica.

10. In an electron-discharge tube, a cathode structure comprising a pair of parallel- 130

disposed, serially-connected conductors at least one of which is a heater ribbon having its flat side facing the other said conductor, an electron-emitting surface adjacent the outer side of said ribbon element, the adjacent facing surfaces of said conductors being insulated from each other.

In testimony whereof, we have hereunto subscribed our names this 26th day of June, 1926, and this 23rd day of June, 1926, respectively.
